PREFABRICATED ROOF

Donald W. Gordon, 124 E. Princeton Road,
Bala Cynwyd, Pa. 19004

Filed Mar. 22, 1971, Ser. No. 127,079

Term of patent 14 years

Int. Cl. D25—02

U.S. Cl. D13—1

Fig. 1

Fig. 4

*Fig. 2.**Fig. 3*

FIG. 1 is a perspective view of prefabricated roof in accordance with the instant invention. The remainder of a structure is shown in phantom lines for purposes of association.

FIG. 2 is a top plan view thereof.

FIG. 3 is a side elevational view thereof. The other three sides appear exactly the same.

FIG. 4 is a bottom plan view thereof.

I claim:

The ornamental design for a prefabricated roof, as shown and described.
